United States Patent Office

Des. 205,915
Patented Oct. 4, 1966

205,915

COMBINED VIEWER AND EDITOR FOR MOTION PICTURE FILM

Bernard A. Barke, Skokie, Ill., assignor to Bell & Howell
Company, Chicago, Ill., a corporation of Illinois

Filed Sept. 20, 1965, Ser. No. 87,060

Term of patent 7 years

(Cl. D61—1)

Fig. 1.

Fig. 2.

FIG. 1 is a perspective view of a combined viewer and editor for motion picture film showing my new design; and

FIG. 2 is a perspective view of the opposite side thereof.
I claim:

The ornamental design for a combined viewer and editor for motion picture film as shown.
